UNITED STATES PATENT OFFICE

PHILIP A. WOOSTER, OF SAN FRANCISCO, CALIFORNIA

DESIGN FOR A TOWEL OR ANALOGOUS ARTICLE

Application filed November 17, 1931. Serial No. 41,753. Term of patent 14 years.

To all whom it may concern:

Be it known that I, Philip A. Wooster, a citizen of the United States of America, residing in the city and county of San Francisco, State of California, have invented a new, original, and ornamental Design for a Towel or Analogous Article, of which the following is a specification, reference being had to the accompanying drawing, forming part thereof.

The figure is a plan view of a towel or analogous article, showing my new design.

It is contemplated that the ornamental diagonal stripe may be applied to the other side of the towel.

I claim:

The ornamental design for a towel, or analogous article, as shown and described.

PHILIP A. WOOSTER.
